US00D884016S

(12) **United States Design Patent** (10) Patent No.: **US D884,016 S**
(45) Date of Patent: **** May 12, 2020**

(54) **DISPLAY SCREEN OR PORTION THEREOF WITH GRAPHICAL USER INTERFACE**

(71) Applicant: **Apple Inc.**, Cupertino, CA (US)

(72) Inventors: **Joseph Chan**, San Francisco, CA (US); **Imran Chaudhri**, San Francisco, CA (US); **Alan C. Dye**, San Francisco, CA (US); **Aurelio Guzmán**, San Jose, CA (US); **Jonathan P. Ive**, San Francisco, CA (US); **Pedro Mari**, Santa Cruz, CA (US); **Alessandro Francesco Sabatelli**, San Francisco, CA (US); **Christopher Wilson**, San Francisco, CA (US); **Eric Lance Wilson**, San Jose, CA (US)

(73) Assignee: **Apple Inc.**, Cupertino, CA (US)

(**) Term: **15 Years**

(21) Appl. No.: **29/703,239**

(22) Filed: **Aug. 26, 2019**

(57) **CLAIM**

The ornamental design for a display screen or portion thereof with graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of a display screen or portion thereof with graphical user interface showing the claimed design; FIG. 2 is a second embodiment thereof; FIG. 3 is a third embodiment thereof; and, FIG. 4 is a fourth embodiment thereof.

The outermost broken lines in the figures show a display screen or portion thereof and form no part of the claimed design. The other broken lines in the figures show portions of the graphical user interface that form no part of the claimed design.

**1 Claim, 4 Drawing Sheets
(2 of 4 Drawing Sheet(s) Filed in Color)**

Related U.S. Application Data

a continuation of application No. 29/635,975, filed on Feb. 5, 2018, now Pat. No. Des. 835,658, which is a continuation of application No. 29/606,298, filed on Jun. 2, 2017, now Pat. No. Des. 809,553, which is a continuation of application No. 29/573,483, filed on Aug. 5, 2016, now Pat. No. Des. 788,808, which is a continuation of application No. 29/501,172, filed on Sep. 2, 2014, now Pat. No. Des. 763,285.
